CLAIM

The ornamental design for a wheel front face, as shown and described.

DESCRIPTION

FIG. 1 is a perspective view of a wheel front face in accordance with the present invention.

FIG. 2 is a front view of the wheel front face of FIG. 1; and, FIG. 3 is a side view of the wheel front face of FIG. 1.

The surface shading is included for the purpose of showing the contours of the claimed design. The broken lines showing the rear of the wheel and rim represent portions of the wheel, and form no part of the claimed design.
